UNITED STATES PATENT OFFICE.

FRANK A. THOMAS, OF CEDAR RAPIDS, IOWA.

DESIGN FOR A WARDROBE-HOOK.

SPECIFICATION forming part of Design No. 32,437, dated April 3, 1900.

Application filed March 5, 1900. Serial No. 7,442. Term of patent 14 years.

To all whom it may concern:

Be it known that I, FRANK A. THOMAS, a citizen of the United States, residing at Cedar Rapids, in the county of Linn and State of Iowa, have invented and produced a new and original Design for Wardrobe-Hooks, of which the following is a specification.

In the accompanying drawings, forming a part of this specification, Figure 1 is a side view of a wardrobe-hook, showing my new design. Fig. 2 is a top view, and Fig. 3 a front view, of the same.

Similar letters of reference denote like parts in all the views.

The general appearance of my new design is that of a bracket, as seen from the side, with an upwardly-inclined loop A at the forward extremity, a semicircle or hook at B, a screw-threaded projection at C, and vertical, horizontal, and diagonal members at D, E, and F, respectively. As seen from above the design presents the appearance of a straight central member, one end of which terminates in the eye of the screw C, which resembles an ordinary screw-eye. Adjacent to the central member and practically parallel therewith for some distance toward the end of the central member opposite the screw appear two adjacent and subjacent members uniting in a loop at the forward end. As seen from

in front the hook B appears as a loop bifurcated downwardly, the member F as slightly diagonal to the vertical, and the adjacent member D as practically vertical, the terminal loop A being vertical and central as respects the looped hook B.

A leading and characteristic feature of the design is seen at G in Fig. 1 and also indicated in Fig. 2, where the inner or rear extremity of the member E appears to hook into the eye of the screw C. This screw, as will be seen, appears as a continuation of the vertical member D, which at the level of the underside of the member E turns forwardly parallel therewith as seen from the side and forms an almost complete circle as seen from above, projecting thence backwardly in a characteristically screw-like form.

Having thus described my invention, what I claim as new, and desire to secure by Letters Patent, is—

The design for a wardrobe-hook, substantially as shown and described.

In testimony whereof I affix my signature in presence of two witnesses.

FRANK A. THOMAS.
